(57) **CLAIM**

The ornamental design for a cart barcode scanner, as shown and described.

DESCRIPTION

FIG. 1 is a perspective view of a cart barcode scanner showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a perspective view showing the state in which the cart barcode scanner is being attached to the handle of a shopping cart; and,

FIG. 8 is a front view showing the state in which the cart barcode scanner has been attached onto a shopping cart. Broken lines and unshaded portions contained within broken lines are not claimed.
